CLAIM

The ornamental design for a cloth, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a cloth, showing my new design; and,

FIG. 2 is an enlarged detail view of the area indicated within the broken lines labeled 2 in FIG. 1.

The broken lines surrounding FIG. 2 and within FIG. 1 denote the boundaries of the detail area and form no part of the claimed design.

1 Claim, 2 Drawing Sheets
(2 of 2 Drawing Sheet(s) Filed in Color)
